SLIPPER

Justin I. Kingson, New York, N. Y.

Application April 1, 1950, Serial No. 8,905

Term of patent 14 years

(Cl. D7—7)

To all whom it may concern:

Be it known that I, Justin I. Kingson, a citizen of the United States, residing at New York, in the county and State of New York, have invented a new, original, and ornamental Design for a Slipper, of which the following is a specification, reference being had to the accompanying drawing, forming a part thereof.

Fig. 1 is a side elevational view of a slipper, showing my new design, the opposite side being substantially the same as the side shown;

Fig. 2 is a top plan view thereof and

Fig. 3, a front view thereof.

I claim:

The ornamental design for a slipper, as shown and described.

JUSTIN I. KINGSON.
